UNITED STATES PATENT OFFICE.

SAMUEL W. MARTIN, OF SPRINGFIELD, OHIO, ASSIGNOR TO MAST, FOOS & CO., OF SAME PLACE.

PUMP.

SPECIFICATION forming part of Letters Patent No. 354,920, dated December 28, 1886.

Application filed October 4, 1886. Serial No. 215,250. (No model.)

To all whom it may concern:

Be it known that I, SAMUEL W. MARTIN, a citizen of the United States, residing at Springfield, in the county of Clark and State of Ohio, 5 have invented certain new and useful Improvements in Pumps, of which the following is a specification, reference being had therein to the accompanying drawings.

This invention relates to improvements in 10 double-acting force-pumps; and the invention consists, essentially, in combining a two-part orseparable head, which receives support from the well-platform, with supporting-pipes, one of which acts also as an air-chamber, and the 15 other of which acts also as a discharge-conduit, with a piston or piston-rod constructed to act upon the water, and with a barrel having the necessary adjuncts to coact with the piston or piston-rod, to form a force-pump, and a cap by 20 which the pipes and barrel are connected together.

Before entering into a detail description of my invention it is proper to observe that in the character of pumps to which this invention 25 particularly relates there are two special classes of double-acting force-pumps. One of these classes is composed of those pumps in which there are two cylinders of unequal diameter, one placed within the other, and in conjunction 30 with which there is a piston-rod having two pistons, one piston for each cylinder. The primary function of the smaller cylinder and its piston is to create a partial vacuum or space, into which water will accumulate when the 35 handle makes its downward stroke, and which will displace that accumulated water on its upward stroke. The other class is composed of one cylinder and a piston-rod constructed at the part within the upper portion of the cylinder, so as to form a piston, as by being enlarged, and having, besides, a plunger at its lower end, which acts in contact with the cylinder. The result in creating the space and in 40 displacing the accumulated water is the same, however, in either case.

In using the term "piston-rod" in this specification and in the claims which follow it will be understood to mean either a piston-rod having one plunger at its lower end, and enlarged 45 near the upper end of the cylinder, or to mean

a piston-rod having two plungers, except in instances where the piston-rod is specifically stated to have two plungers.

In the accompanying drawings, forming a part of this specification, and on which like reference letters indicate corresponding features, Figure 1 represents a vertical sectional view of my improved pump; Fig. 2, a like view of the upper portion of the pump on a larger scale; Fig. 3, a horizontal sectional view of the 55 head on the line xx of Fig. 2, and Fig. 4 a sectional view of the cylinder and the form of piston having an enlarged portion.

In the drawings, A designates the cylinder or barrel, constructed of tubular form and of 60 the same size from end to end. The lower end is supplied with the usual suction-pipe (not shown) and the upper end with cap B, which screws into the barrel or outer cylinder, and which has a tubular extension, C, that connects, as by a screw-thread, with the barrel or inner cylinder, D, and supports the same. The cap is further provided with vertical openings, into which the pipes E and F are respectively secured. The tubular extension C 65 forms an opening through which the piston or piston-rod G passes on its way into the barrel.

The structure so far described is suspended 70 from above, and as in deep wells the pipes and the piston or piston-rod must be of considerable length, thereby rendering the parts liable to sway, it becomes necessary to hold the upper ends of the pipes firmly and by as long a bearing or contact with the head as practicable. This is done successfully by the head 75 indicated by the letter G'. This head is constructed of two parts divided vertically and held strongly together by the bolts H, which

pass through them. The parts are hollow, and each is provided with an interior flange, I, 80 near the bottom, and a like flange, J, near or at the top, and each flange or bearing is constructed with semicircular or similar recesses, K K and L. When the parts are secured together, these recesses register, and those designated K K encircle and tightly bind and secure the pipes E and F, while those designated L afford a passage for the free vertical movement of the piston or piston-rod, which passes 85 on up, and is connected with an operating. 90

handle, M, fulcrumed in the vertical extension N of the head.

The pipe F is closed at its upper end, as seen in Fig. 2, and thus forms an air-chamber, as well as a supporting-pipe, while the pipe E has a spout at its upper end, and thus forms a discharge-pipe, as well as a supporting-pipe.

Each part of the head is constructed in open-work for admitting air to the interior and beneath the platform for the purpose of ventilation. The two parts of the head admit of the pipes and piston-rod being easily enveloped, even though the spout and the handle are in place, and of the pipes being firmly clamped and held, while at their lower ends they are secured to the barrel by the cap. Thus the structure is cheaply and strongly united together, and still the leading ideas of the invention preserved—namely, the barrel and the supporting-pipes connected by a cap, the piston-rod passed through the cap and the pipes held firmly, and an elongated head at the top of the well, and all this without increasing the lateral dimensions.

Having thus fully described my invention, what I claim as new, and desire to secure by Letters Patent, is—

1. In a pump, the combination, with a two-part vertically-divided head constructed to rest upon the platform and provided with interior clamping-bearings and with central openings, and devices to secure the parts of the head together, of supporting-pipes fitted to the said bearings of the head and clamped and held thereby, the cap secured to the lower ends of said pipes and having a piston-rod

opening, a pump-barrel secured to the cap and extending below it, and a piston-rod passing through the cap and the said central openings.

2. In a pump, the combination, with a vertically-divided head constructed to rest upon the platform and having upper and lower interior bearings or flanges and central openings, and devices to secure the parts of the head together, of two upright pipes placed side by side, one forming an air-chamber and the other a discharge-conduit, and a cap secured to said pipes and having a central opening, said cap forming a support for the lower part of the pump in connection with said pipes.

3. In a pump, the combination, with a vertically-divided head constructed to rest upon the platform and having upper and lower interior bearings or flanges and central openings, and devices to secure the parts of the head together, of two supporting-pipes placed side by side and clamped between the flanges of the head, one forming an air-chamber and the other a discharge-conduit, a cap secured to said pipes and having a central opening, and a tubular extension, a pump-barrel also secured to the cap, and an inner cylinder secured to the extension, and a piston-rod having two plungers, one for each cylinder, and passing through the cap and the said central openings in the head.

In testimony whereof I affix my signature in presence of two witnesses.

SAMUEL W. MARTIN.
